DRAFT TUBE.

Application filed October 4, 1927. Serial No. 224,016.

This invention relates to draft tubes, and particularly to the elbow type formed of concrete or other analogous material, or in some instances formed of metal. The present invention embodies an improvement of the structure disclosed by the pending application of George A. Jessop, improvements in draft tubes, filed March 11, 1925, Serial No. 14,850. The same structural advantages 10 in draft tube structure are sought and desired to be maintained in the present structure as in the original improved elbow draft tube disclosed by the aforesaid application, the material variation in the structure of the 15 outlet leg of the tube and a more efficient result in operation being the distinguishing features of the present improvement. It has been discovered that there is a higher 20 velocity at the bottom and outside edges of the tube than at the top center from points starting well into the downstream curvature of the elbow and continuing to the outlet of the tube. This variation in velocity begins 25 shortly after the tube starts to bend, and becomes a maximum at or near the end of the elbow and decreases towards the outlet. In order to obtain the best possible efficiency 30 in a draft tube of the elbow, or any other type, it has been found necessary to so form the tube that the water remains in full flowing contact with all surfaces of the tube, which is accomplished to a very material 35 extent by a novel curvature of the elbow in this class of elbow draft tubes, as specified in the aforesaid application. In accordance 40 with the features of this improvement a more efficient and complete or full flowing contact with the surface of the outlet leg of the tube is obtained by filling in the top 45 of the tube at the center along the horizontal leg and for a distance upwardly into the downstream portion of the elbow top curve, and thereby overcome the formation in the 50 tube of a comparatively dead space at the center and top of the horizontal leg or outlet 55 portion of the tube, and thereby secure a more even distribution of water in all parts of the tube. As the water flows downwardly 60 through the tube from the entrance and is gradually turned from a vertical direction 65 by the upstream curvature of the elbow, there is a natural spreading effect which increases and becomes more noticeable at what

may be termed each section of the elbow organization. At the beginning of the upstream curvature of the elbow section the spreading effect is slight and becomes greater in the successive portions or sections thereof until its reaches its maximum at or near the final section and where the elbow 55 merges into the outlet or horizontal leg of the draft tube. The velocities in these tubes, particularly when used for turbines under very large heads, are quite high, and the spreading action is therefore quite rapid 60 and causes a large portion of the water to pass to the outside curved periphery of the tube at the final sections of the elbow or near the terminal of the latter situated adjacent to the horizontal leg of the tube outlet. The water at the outside of the tube is therefore assuming a spiral motion but flows 65 forwardly along the tube at a more rapid rate than its rate of spiral revolution, the spiral movement of the water being insufficient to force or throw the water to the center 70 of the tube and permitting a void to be formed at the center of the tube, which should be filled or rectified by change of 75 shape of the tube to eliminate eddies and 80 partial voids.

The general operation of the present tube within the length of the curvature complete 85 is the same as that disclosed in the pending application above noted, but in the present structure there is a modification of structure to attain a more satisfactory and complete 90 operation and thereby overcome the slight disadvantages present in the prior structure. The improvement set forth herein is particularly advantageous where it is desirable to install elbow draft tubes of comparatively 95 small vertical height and short horizontal length. The improved elbow has the same curvature on the upstream surface and the same shape at the bottom of the horizontal leg, and it has the same construction and easement curves on the downstream, or upper, side of the elbow bend, throughout the 100 bend at the outside portions. The center portion of the upper side of the elbow bend, near the end of this part of the tube, is modified by filling in, or reducing the area by means of a flat top of novel form, with, preferably, approximately straight sides. 105 It is not intended that the improved draft

tube be limited to any particular rate of increase of area or to any particular rate of decrease of velocity. Further, in the present improved structure, wherever it is possible, this flat roof portion embodies a straight line construction and the curved, or circular, sides of the prior structure are replaced with vertical sides, sometimes straight fillets at the farthest possible upstream section of the tube consistent with satisfactory results. This simplifies and cheapens the work required to construct the tubes, whether made of concrete, metal or other material.

The object of the present invention therefore is the provision of a flat top portion for the horizontal leg or outlet of the draft tube in contradistinction to a top curved contour to obtain a more uniform velocity at the outlet together with a novel arrangement of piers within the horizontal outlet to secure a more uniform flow of water through the horizontal leg with the greatest possible reduction of velocity from the entrance of the outlet of the tube, and whereby the formation of a dead space at the center and upper portion of the horizontal leg is entirely avoided and a more even distribution of the water over the remaining passages is obtained, thus overcoming the disadvantage of having the water break away in the top or downstream curve of the elbow.

The present invention consists essentially in the preferred construction and arrangement of parts which will be more fully hereinafter described and claimed.

The accompanying drawings illustrate the improved draft tube formed of concrete or analogous cementitious material, but it will be understood that the same essential features of invention may be included in a metal or sheet steel draft tube.

In the drawings:

Fig. 1 is a longitudinal vertical section through an elbow draft tube embodying the improved features of the invention.

Fig. 1^a represents a section taken horizontally through the upper end of the draft tube shown in Fig. 1, the top flange being omitted.

Fig. 2 is a horizontal section on the line 2. 2. Fig. 1.

Fig. 3 is a horizontal section on the line 3. 3. Fig. 1.

Fig. 4 is a horizontal section on the line 4. 4. Fig. 1.

Fig. 5 is a transverse section on the line 5. 5. Fig. 1.

Fig. 6 is a transverse section on the line 6. 6. Fig. 1.

Fig. 7 is a transverse vertical section on the line 7. 7. Fig. 1.

Fig. 8 is an end elevation of the outlet terminal or horizontal leg of the tube.

Fig. 9 is a horizontal section taken through

the center of a part of the tube, and particularly through the outlet or horizontal leg and containing rearwardly a distance through the elbow bend, the upper inlet of the elbow being shown in dotted lines.

The numeral 5 designates a concrete or other cementitious structure in which the improved tube is suitably formed, the latter comprising an upper inlet extremity 6 over which the runner or wheel is adapted to be mounted in the usual manner. The concrete or other analogous structure 5 may be continued upwardly any suitable distance to serve as a base support for the installation of the remaining part of a turbine or other water power organization, and also for the purpose of supporting a power house in which the turbine unit or units are disposed. The upper member 7 of the improved draft tube is shown as composed of sheet metal down to the point 8, the remaining part of the draft tube being shaped in the concrete or other material. It will be understood that the upper member 7 of the draft tube, which may be specified as the "inlet member" may in some instances be constructed or shaped in the concrete. This upper inlet member 7 to a point a short distance below the plane of section 2. 2. is concentric with relation to the axial line 9^a which is also the vertical axis of the runner or wheel and the turbine shaft. The upper inlet member 7 may be slightly bowled and regularly flares in a downward direction as shown, or it may have a straight taper or flare.

At a comparatively short distance below the plane or section on the line 2. 2. and as indicated by the plane of section 3. 3. Fig. 3, the draft tube begins to assume an elliptical contour, and this configuration increases gradually in the present instance through to the plane of the section 6. 6., as indicated by Figs. 3 to 6 inclusive. In order to arrive at this construction, the curve 11 of the upstream or lower side of the elbow begins prior to the curve 12 of the downstream or forward upper wall of the draft tube elbow. The rear or upstream curve 11 comes from the vertical to the horizontal in an arc with a practically constant radius, or in other words, with a constant curvature. The curvature of the downstream or upper face of the elbow starts at a materially lower elevation than the upstream curve 11 when considering a vertical tube construction only. In other words, the curvature 12 of the downstream face of the elbow in the downstream direction starts much later than the curvature 11 of the upstream face. This downstream curve 12 of the upstream face is an easement curve, that is, at the beginning thereof there is a long radius of curvature and this radius is gradually decreased and becomes a minimum at or near the end of the curve as at 9 for

the outside portion of the tube, and as at 13 for the central portion of the tube. In a vertical setting the points are about at the horizontal. From the point of the plane of 5 the section 7. 7. to the point 13 or end of the easement curve there is a modification of structure in the present improved invention relatively to that disclosed in the prior application heretofore noted for the purpose 10 of assisting the water to remain in a more perfect full flowing contact with the downstream or upper portion of the elbow of the draft tube, and assist in maintaining a practically equal velocity of water at a given 15 section of the draft tube. The maintenance of an equal velocity at all points in a given section of a draft tube, said section being taken approximately at right angles to the longitudinal center line, is necessary in order 20 to maintain smooth flow and high efficiency in the tube. Again, for the purpose of illustration, let it be assumed that the tube is divided into three distinct parts. The first 25 part is the vertical section or inlet member 7 with a straight vertical center line immediately below the runner. The sections at this inlet part or member of the tube are true, or approximately true circles, and for convenience of description the words "breadth" and 30 "width" will be applied to different sections of the tube, the "breadth" being intended to mean the distance between the walls of the tube as cut by a plane passing through a longitudinal center line thereof, and by 35 "width" is meant the distances between the wall of the tube as measured at right angles to the foregoing plane, each measurement passing through the longitudinal center line of the tube.

40 The second part of the tube is the curve or elbow section 10. The breadth of the tube is a maximum at approximately the end of the first part and at approximately the beginning of the second part 45 or section or elbow 10. The breadth of the second part or elbow member 10 relatively decreases from its maximum at the entrance of this second part or section to its minimum at or near the end of the elbow, 50 as at 9 and 13. In other words, the upstream or lower face of the draft tube defined by the curve 11 approaches and gets nearer to the downstream or upper face of the draft tube defined by the curve 12. At 55 the same time the width or lateral extent of the draft tube is increased all along the bend or elbow section 10, and this increase is such that the area of the tube is constantly increasing, so that the velocity of the water 60 in the tube is constantly decreasing, or the velocity head is constantly being converted into pressure head. The reduction in the breadth of the tube from the beginning of the upper end of the second section or part 65 or elbow 10 is accomplished by making a

curvature of the upstream and downstream faces of the tube, or the lower and upper sides of the tube, in the curvature heretofore specified, and further because the curvature of the downstream or upper face or 70 side is started at a considerably lower point or later than the curvature of the upstream or lower face.

The third part of the sectional tube is the horizontal leg 15 which serves as the 75 outlet. Both the breadth and width of this leg may increase gradually, but it is unnecessary that both increase, in view of the fact that one dimension, for instance, the vertical extent of the leg, could remain constant and 80 even be decreased, provided the width or lateral extent of the tube be increased a sufficient degree to maintain the continuously increasing area as the water approaches nearer and nearer the outlet end 16. As 85 hereinbefore indicated, from the entrance of the improved tube to the outlet end thereof the area is continuously increasing and therefore the velocity of the water is continuously decreasing.

The present improvement, in view of the structure heretofore disclosed and the co-pending structure disclosed by application Serial No. 199,530, filed June 17, 1927 in the name of George A. Jessop, preserves in the 90 main the same structural conditions as just enumerated with structural modifications or changes in the upper part of the outlet leg or section 15, and continues in the same plane into the downstream part of the elbow 100 as far upwardly as about the plane of the section indicated by the line 4. 4. shown by Figure 1, and which consists in directing the curve 12 at the center of the downstream curve of the tube with a longer series of 105 radii than the similar easement curve in the original disclosure of the co-pending application Serial No. 14,850 at the downstream or upper portion and the similar curve is used in the construction of the elbow at the 110 outside portion of the elbow bend, the said curve 17 continuing to depart regularly from the curve 17^a until it reaches about the point 13 where it gradually merges into a flattened top portion 18 of the outlet leg 115 15. The present improvement comprises two supporting piers 19 and 20, as clearly shown by Figure 9, and are located on opposite sides of the longitudinal center of the outlet end 16 of the leg. As indicated by the cross sections, in Figures 6 and 7 the flat top assumes an upward trend or inclination fully from the outer portion of the elbow to the end 16 of the leg 15, and extending partially inwardly and upwardly to the top 120 or downstream curve of the elbow or as near as far back inwardly and upwardly as approximately the plane of the section 5. 5. The opposite sides of the elbow as shown by Figures 3 and 4 are curved as at 21, but this 125 130

curvature gradually merges or is changed into nearly straight or vertical side structures as at 22, Figures 5, 6, 7 and 8, and the angular corners formed by the intersections 5 of the outlet extremity of the sides of the point of change to the vertical structure being filled at top and bottom by fillets 23, as shown by Figures 5 and 6 for a portion of the length of the leg 15, or, to compensate 10 for a change of the configuration until there is a full side emergence into full vertical structures, shown by Figures 7 and 8. Hence the outlet leg 15 of this further improved form of draft tube as compared to the structure disclosed by application Serial No. 14,850 heretofore referred to, is filled at 15 points which aid in overcoming the tendency of the water to break away from the top or downstream curve of the elbow at 20 the plane of the sections 4 and 5 for instance, and eliminating from the tube the comparatively dead space at the center of the top of the horizontal leg 15 and obtaining a more even distribution of the water over the remaining 25 passages and also avoiding a tendency to spiral motion of the water along the side portions of the leg, the latter having at the top a substantially straight line construction. The piers 19 and 20 are positioned 30 with the upstream ends thereof close to the side walls of the tube. As indicated, the velocity at the side walls is somewhat higher than at the center, and therefore, the greatest quantity of water 35 passes out of the tube along the sides. These piers collect some of this water from the sides and distribute it smoothly and efficiently to the center of the tube. The piers are sloped or converged away from the 40 outside of the tube and toward each other. The slope or convergence must be such that the outside sections of the tube formed between the piers and the side walls will maintain 45 the water in full flowing contact with all surfaces of this part of the tube, the piers approaching each other in the center. The water in this part of the tube will, of course, remain in full flowing contact with all surfaces. By these piers as shown, the velocity 50 at the center of the draft tube can be made approximately equal to that outside, thus securing uniform velocity and materially increasing the efficiency of the draft tube.

Furthermore, these piers 19 and 20 will 55 also serve as supports for a power house structure and also strengthen the outlet leg.

This improved structure of elbow draft tube produces full flowing water contact with all sides throughout the length of the 60 tube, and the water is gradually decelerated towards the outlet end 16 of the tube and is finally discharged into the tailrace.

What is claimed as new is:—

1. A draft tube having an inlet extremity 65 concentric with relation to a central axis

and continuing into an elbow which is gradually decreased in breadth from the upstream towards the downstream portion thereof by an upstream, practically constant radius curve and a downstream easement 70 curve, the draft tube being increased in width and terminating in an outlet extremity having means therein for equalizing the velocity of the water flow downstream throughout the width thereof. 75

2. A draft tube having an inlet extremity concentric to a central axis and continuing into an elbow which is gradually decreased in breadth from the upstream towards the downstream portion thereof by means of an 80 upstream, practically constant radius curve and a downstream easement curve and proportionately laterally increased in width and terminating in an outlet leg, the said outlet leg having a flattened form and having means therein for increasing the velocity of the water flowing through its central portion relatively to that of the water flowing along its sides, the draft tube from its inlet 85 to its outlet extremity increasing in area 90 as a whole.

3. A draft tube comprising an inlet member and an outlet leg with an elbow therebetween, the said elbow being decreased in breadth from the upstream towards the 95 downstream portion thereof by means of an upstream, practically constant radius curve and a downstream easement curve, said easement curve starting at a materially lower elevation than said constant radius curve, and the said elbow bend being correspondingly and proportionately increased in width, the outlet leg having a flattened form 100 and having means therein for reducing the velocity of the water flowing along its sides 105 relatively to that of the water flowing at its center.

4. A draft tube having inlet and outlet extremities with an elbow bend therebetween, the inlet extremity being circular and the 110 tube as an entirety from its inlet extremity being increased in lateral extent and continuing with this lateral increase throughout the elbow in a direction from the upstream to the downstream portion of said elbow bend, the elbow bend having an upstream, practically constant radius curve and a downstream easement curve, the outlet extremity having a transversely straight flattened top portion with piers therein on opposite sides of the center converging towards the end of the outlet extremity. 115

5. A draft tube having inlet and outlet extremities with an elbow bend therebetween, the inlet extremity being circular and the 120 tube as an entirety from its inlet extremity being increased in lateral extent and continuing with this lateral increase through the elbow in a direction from the upstream towards the downstream portion of said 125 130

bend, the elbow bend having an upstream, practically constant radius curve and a downstream easement curve, the outlet extremity having a transversely flattened form and having means therein for relatively reducing the velocity of the water flowing along its sides and for relatively increasing the velocity of the water flowing at the intermediate portion of its width.

10 6. A draft tube having inlet and outlet extremities with an elbow bend therebetween and gradually increased in lateral extent from the inlet extremity which is circular in contour to the outlet leg at a distance beyond the termination of the elbow bend, the elbow bend correspondingly and gradually increasing in lateral extent throughout the formation thereof towards the outlet extremity, the elbow bend having an upstream, practically constant radius curve and a downstream easement curve, the elbow also gradually decreasing in vertical extent towards the outlet extremity, and the outlet extremity having a flattened form and having piers arranged angularly therein to increase the velocity of the water flowing intermediately of its width relatively to that of the water flowing at its sides.

7. A draft tube having inlet and outlet extremities with an elbow bend interposed between said extremities and continuous therewith, the said elbow being materially flattened in a transverse vertical direction within the area of the bend portion thereof and also increasing in width within the area of the bend and regularly continuing into the outlet extremity, the elbow bend having an upstream, practically constant radius curve and a downstream flattened contour which is transversely straight and having an outlet leg and piers therein arranged angularly with respect to its sides to reduce the velocity of the water flowing at the sides of the leg relatively to that of the water flowing through the portion thereof intermediately of its width.

8. A draft tube having inlet and outlet extremities and an elbow bend between the two extremities, the inlet extremity being concentric with relation to a central axis and regularly continuing into the elbow bend, the elbow bend regularly decreasing in breadth by an upstream constant radius curve and a downstream easement curve differing from the upstream curve, the said bend also positively increasing in width divergently, and said divergence regularly and fully continuing into the outlet extremity of the tube, the outlet extremity of the tube having a transversely straight flattened top and straight side portions, the said flattened top portion of the outlet extremity extending a distance rearwardly into the elbow bend, and the opposite curved sides of the bend merging into vertical sides of the said outlet

extremity, the said outlet extremity also having a pair of piers disposed on opposite sides of the center thereof and converging towards the outer end of the said outlet extremity.

9. A draft tube having inlet and outlet extremities and an elbow bend between the said extremities, said elbow bend at the upstream portion having a curve which comes from the vertical to the horizontal in an arc of a circle and the opposite or downstream portion having an easement curve which is formed in the center with a dip towards and merging into the top of the outlet extremity and providing an easement curve with less rapid change of curvature at its terminal and which merges into the outlet extremity which has a transversely flattened form having water directing members which extend longitudinally therein, said members converging towards one another and diverging from the adjacent sides of the flattened outlet in a direction towards the end of the outlet extremity.

10. A draft tube having inlet and outlet extremities with an elbow therebetween, the elbow being contracted in breadth and expanded in width and the outlet extremity having a transversely flattened portion and means in said outlet extremity for increasing the velocity of the water flowing in the center relatively to that of the water flowing at the sides thereof.

11. An elbow draft tube having an inlet extremity concentric with relation to a central axis and wherein also the elbow bend is contracted in breadth and expanded in width and continued into an outlet leg with an upwardly flaring top portion, said outlet leg being transversely flattened and having therein means to increase the velocity of the water flowing in its center and to relatively decrease the velocity of the water flowing along its sides.

12. A draft tube having a circular inlet, an elbow bend contracted in breadth and expanded in width and continuous with said inlet and operating to cause a round column of water entering the draft tube ahead of the elbow bend to be flattened in breadth and expanded in width, and an outlet extremity having a flattened top which is transversely straight and upwardly flares from the said elbow bend and is provided with a pair of piers on opposite sides of the center which converge relatively to one another in a direction towards the end of the outlet extremity to eliminate eddies and voids.

13. A draft tube having an intermediate elbow bend flattened in breadth and expanded in width and an outlet extremity with a transversely straight flattened top portion extending from the elbow bend to the end of the outlet extremity and also provided with a pair of piers in the outlet extremity and

spaced from the sides thereof, the opposed surfaces of said sides and the respective spiers gradually diverging towards the end of the outlet extremity.

- 5 14. A draft tube having inlet and outlet portions with an elbow therebetween, the elbow being contracted in breadth and expanded in width in a direction from its inlet towards its outlet and the outlet portion having water outlet passages at its sides which increase in area in a downstream direction and having an intermediate water outlet passage which decreases in area in a downstream direction.
- 10 15. A draft tube having inlet and outlet

portions with an elbow therebetween, the elbow being contracted in breadth and expanded in width in a direction from its inlet towards its outlet and the outlet portion having water outlet passages at its sides which increase in area in a downstream direction and having an intermediate water outlet passage which decreases in area in a downstream direction.

In testimony whereof I have hereunto set my hand.

JAMES D. SCOVILLE.
